ELECTRICAL SWITCH

Malcolm Lee Goodwin, Culver City, Calif., assignor of fifty-two per cent to Phil Sheoridon Emery, Culver City, Calif.

Application April 1, 1937, Serial No. 134,380

2 Claims. (Cl. 200—3)

This invention appertains to new and useful improvements in automobile electrical systems and more particularly to novel means whereby the headlights and tail-lights of an automobile 5 may be made to blink to indicate that the driver intends to make a right or a left turn.

The principal object of the present invention is to provide a blinking means for the usual light system of an automobile whereby the headlights 10 and tail-light can be discretionarily blinked as a signal and wherein the means for accomplishing this function is simple and easily installed and capable of being put out of service without interfering with the lighting system.

15 These and various other important objects and advantages of the invention will become apparent to the reader of the following specification.

In the drawings:

Figure 1 represents a diagrammatic view of 20 the lighting system and the switch.

Figure 2 is a top plan view of the switch with the cover removed.

Figure 3 is a fragmentary enlarged vertical sectional view with the cover applied.

25 Figure 4 is a sectional view taken substantially on the line 4—4 of Figure 2.

Referring to the drawings wherein like numerals designate like parts, it can be seen in Figure 1, that numerals 5—6 represent the usual headlights and numerals 7—8 the usual tail-lights. Numeral 9 denotes the usual battery from which the lead 10 extends and in which the light switch 11 is installed.

30 Numeral 12 denotes the novel switch construction for controlling the light dimmer and this consists of the case 13 of dielectric material having a removable top 14. The side wall of this case 13 is provided with a circumferentially disposed slot therein through which the arm 15 35 projects, the arm being swingably secured as at 16 to the central portion of the case 13 and having the finger 17 projecting therefrom and carrying the contact blade 18 capable of bridging the contacts 19—20 secured to the inside of the 40 side wall of the case 13.

The outer end of the arm 15 is provided with a handle 21.

The case 13 is provided with a pair of diverged protuberances 22—23 each provided with 45 a pocket 24 therein for receiving a contact coil unit 25 of conventional design. This unit is of the type which heats up to make contact and breaks contact upon cooling off. This action is rapid and causes a rapid intermittent flow 50 of current. The contact strip 26 has a pair of

5 contact flanges 27 thereon, this strip 26 being disposed in the pocket 24 for forming an arcuate contact member 28. A contact strip 29 has a backwardly bent arcuate contact extension 30 opposed to the arcuate contact 28 and between 5 these contacts 28—30 the unit 25 can be inserted. The contact 29 has a binding post 31 from which the conductor 32 extends to the corresponding headlight 5 or 6 and its corresponding tail-light 7 or 8. Obviously when the contact blade 10 18 is engaged with either of the contacts 27—27 current will be supplied to either the left or right headlight and its corresponding tail-light 7 or 8. The contacts 19—20 are connected by the jumpers 33 to the binding posts 31 so that 15 when the blade 18 is bridging both of the contacts 19—20, both of the headlights and tail-lights will burn steadily without blinking.

As is clearly shown there are a pair of contact members 34—34 mounted upon the bottom 20 of the case 13 and from these extend the wires 35 to the binding posts 31. Obviously as the blade 18 is engaging one of the contacts 27 the arm 15 is engaging one of the contacts 34, so that while current is passing from the arm 15 25 and contact 26 to one headlight by way of a blinker 25, current is supplied to the other headlight clear of its blinker unit 25.

While the foregoing specification sets forth the invention in specific terms, it is to be understood that numerous changes in the shape, size and materials may be resorted to without departing from the spirit and scope of the invention as claimed hereinafter.

Having described the invention, what is 35 claimed as new is:

1. A switch of the class described comprising, a casing, a pair of terminal posts carried by the casing, a switch arm pivotally mounted in the casing intermediate the ends of the arm with 40 one end part of the arm projecting from the casing, a first pair of contacts in the casing and one connected with one post and the other with the opposite post, a second pair of contacts in the casing and one located adjacent but spaced 45 from one of the first mentioned contacts and the other located adjacent but spaced from the other contact of the first-mentioned pairs, a pair of temperature actuated units located in the spaces between the first and second pairs of contacts, 50 a third pair of contacts in the casing bridged by the inner end of the arm when the arm is in a certain position, means for electrically connecting one of the third pair of contacts with one post, means for electrically connecting the 55

other contact of the third pair with the other post, said arm when in a second position engaging one of the second pair of contacts and when in a third position engaging the other contact 5 of said second pair, a fourth pair of contacts in the casing, each of which is arranged opposite a contact of the second pair, whereby when the arm is engaging a contact of the second pair another part of the arm will be engaging a contact of the fourth pair, means for electrically 10 connecting one contact of the fourth pair to one post, means for electrically connecting the other contact of the fourth pair to the other post, and means for electrically connecting the arm 15 to a source of current.

2. A switch of the class described comprising a casing of non-conductive material having a pair of pockets therein, a terminal post extending from each pocket, a contact in each pocket and connected with the post of said pocket, a second contact in each pocket, the two contacts in each pocket having resilient portions spaced apart, a temperature actuated unit in

each pocket and located in the space formed by said resilient parts, a third pair of contacts in the casing, means for electrically connecting one of the third contacts with one post, means for electrically connecting the other contact of the 5 third pair with the other post, a fourth pair of contacts in the casing, means for electrically connecting one contact of the fourth pair with one post, means for electrically connecting the other contact of the fourth pair with the other 10 post, an arm pivoted intermediate its ends in the casing and having a handle part extending from the casing, said arm in one position bridging the contacts of the third pair to provide an uninterrupted flow of current to the posts and 15 said arm when in another position bridging one of the contacts of the second pair and a contact of the fourth pair and when in a third position bridging the other contacts of the second and fourth pairs and means for electrically connecting the arm to a source of current. 20

MALCOLM L. GOODWIN.
